DENTAL APPARATUS

Roy E. Hawkinson, Detroit, Mich.

Application May 21, 1940, Serial No. 336,428

3 Claims. (Cl. 32—29)

The present invention relates to a guard for dental tools and is useful in connection therewith to prevent injury to the tongue or other oral tissues during the performance of various treating operations on human teeth. More particularly, the invention relates to apparatus which includes a cutting or grinding implement mounted on a mandrel, a hand piece for guiding the implement, and a guard carried by the mandrel which is so arranged as to permit a ready manipulation of the implement while, at the same time, the guard protects the tongue against injury from the implement.

It has been proposed heretofore to provide an extending attachment secured to and carried by a dental mandrel which is held in the hand piece. Such attachment is intended to act as a guard to protect the tongue from injury by the tool on the mandrel. These attachments have been of different constructions, sizes and shapes. In general, however, they have included a portion which caps or partially encloses the grinding or cutting implement. Such attachments have heretofore proved unsatisfactory principally because they are cumbersome and inconvenient in use and obstruct the user's line of vision.

One object of the present invention is to provide a dental guard member carried by the mandrel which is operative to protect the tongue, cheeks, lips, or other parts of the oral cavity from injury during use of a dental implement for treating the face or side surfaces of a tooth, the guard member providing an unobstructed line of vision to parts of the tooth or teeth under treatment.

Another object of the invention is to provide a dental hand piece assembly in which the shank or mandrel of a grinding disk or other dental implement is journaled within an arm extending from a plate-like guard member which permits resting of the plate-like guard member within the oral cavity to hold the tongue or cheeks of the patient at a predetermined safe distance from the cutting or grinding implement without obstructing the user's line of vision or impairing his facility in handling the implement.

Other objects and advantages of this invention will appear in the following description and appended claims, reference being had to the accompanying drawing forming a part of this specification wherein like reference characters designate corresponding parts in the several views.

Fig. 1 is a top plan view of one embodiment of the present invention placed within the oral

cavity in a position to effect a grinding operation on one of the lower teeth.

Fig. 2 is a perspective view of the form of the invention shown in Fig. 1.

Fig. 3 is a side elevation partially in section of the form of the invention shown in Figs. 1 and 2.

Before explaining in detail the present invention it is to be understood that the invention is not limited in its application to the details of construction and arrangement of parts illustrated in the accompanying drawing, since the invention is capable of other embodiments and of being practiced or carried out in various ways. 15 Also it is to be understood that the phraseology or terminology employed herein is for the purpose of description and not of limitation.

Referring to the drawing, the reference numeral 10 indicates, in general, a guard member forming a part of dental apparatus embodying the present invention. This member includes a plate-like portion 11 provided with an extending arm 12. The member 10 may be made of any suitable material, preferably a non-corrosive metal, and the arm 12 may be attached thereto by any suitable means or may be made integral therewith. While the plate 11 is preferably provided with rounded corners, as shown, it may be of any suitable size and shape. For example, it may possess rounded marginal edges, flanges, turned portions, or the like. The member 10 is adapted to be inserted within the oral cavity in the manner clearly shown in Fig. 1 and is adapted to rest on suitable portions of the body therewithin. For instance, it may rest on the floor of the mouth, at the base of the teeth, or on the gums. In this connection, the aforementioned flanges or turned portions of the plate 11 may be made suitable to conveniently rest on or to contact a contemplated portion of the body within the oral cavity. For instance, a turned marginal edge of the plate 11 could engage the tongue 13.

The arm 12 is provided at its free end with an enlarged head 14. This head is provided with a bearing portion indicated generally at 15 (Fig. 3), which rotatably supports the mandrel 20 of the dental implement 18. The head 14 may possess a central longitudinal bore within which the mandrel 20 is mounted for rotation. If desired, some other suitable bearing construction may be provided so that the mandrel 20 is journaled for rotation in the arm 12.

The reference numeral 18 indicates, in general, a dental implement adapted to effect treat-

ing operations on teeth. In the form of the invention shown in the drawing, this implement 18 comprises a grinding disk 19 attached to the end of the mandrel 20 by the nut 21 or a screw (not shown). The mandrel 20 extends within the longitudinal central opening or bore of the head 14. A collar 23 is secured to the mandrel to prevent unintended displacement of the mandrel from the head 14 and to prevent uncontrolled longitudinal movement of the mandrel in the bore of the head 14. The shank 25 of the mandrel connects the mandrel 20 with the hand piece 26. A set screw 23a is provided to adjustably secure the collar 23 to the mandrel 20.

The end of the shank 25 is inserted within a gripping portion or chuck of the dental hand piece 26. The construction of this hand piece is conventional and is therefore not described in detail herein. However, such hand pieces normally include a chuck or clamping element for rigidly engaging a shaft or shank, such as the shank 25, and are provided with adjustable gripping means or jaws allowing the ready insertion and removal of such shanks. For instance, the hand piece may be provided with a revolvable collar 27 for controlling the gripping means or jaws. Also the hand piece 26 is provided with a shaft 28 extending therethrough which is rigidly fixed to the shank 25 for rotating the same by means of the aforesaid chuck or clamping elements. This shaft 28 may be protected by a suitable sheath as shown at 29. In view of the foregoing it will be understood that rotation of the shaft 28 will rotate the mandrel 20 and the grinding disk 19.

It will be appreciated that suitable variations in structure may be made in the bearing 15, and also that the mandrel 20 may be connected for rotation with the shaft 28 by any suitable means. For example, the mandrel 20 may continue through the bearing 15 and be directly connected with the hand piece 26 for rotation by the shaft 28, thereby eliminating the collar 23. Also, it will be appreciated that the dental implement 18 need not consist of a separate mandrel and member attached thereto. This implement may be of a one-piece construction having a suitable shank performing the functions of the mandrel 20 and a suitable head performing the functions of the member 19. Moreover, various dental implements may be used in the present apparatus although a grinding disk is shown in the drawing. For instance, a dental drill, buffer or the like may be employed instead of the disk here shown.

After the dental implement 18 has been assembled relative to the hand piece 26 and supporting member 10 in the manner indicated heretofore, the present dental apparatus is ready for use. When the apparatus is inserted within the oral cavity, the plate 11 forming a part of

the member 10 contacts the tongue 13 and spaces it from the dental implement, thereby protecting the tongue from injury by the said implement. Also, it will be noted that the member 10 provides an unobstructed line of vision to the tooth being treated, for it does not enclose or cover the implement 18 and, in addition, prevents the tongue from doing so. In this connection, the member 10 may be easily maneuvered within the oral cavity so that the entire apparatus may be guided and directed by the user with a minimum amount of effort.

From the foregoing it will be appreciated that the member 10 need not be positioned as shown in the drawing, but may be positioned in any suitable way best suited for the dental operation contemplated. For instance, it may be inserted outside of the teeth, in which case the plate 11 will press against the lip or cheek instead of the tongue as illustrated in Fig. 1. The plate 11 is so formed and dimensioned and mounted on the mandrel 20 that it may be used equally well on either side of the mouth.

I claim:

1. In a dental tool of the class wherein a cutting element is fixed to the end of a rotatable mandrel, the combination with said mandrel of a tongue guard directly mounted thereon for free rotational movement thereabout, normal to the plane of the cutting element and arranged in protective relation with respect to a portion of the periphery of said cutting element.

2. In a dental tool of the class wherein a cutting element is fixed to the end of a rotatable mandrel, the combination with said mandrel of a tongue guard directly mounted thereon for free rotational movement thereabout, normal to the plane of the cutting element and arranged in protective relation with respect to a portion of the periphery of said cutting element, and means on said mandrel cooperating with said guard to position said guard adjacent said cutting elements and to maintain said guard against displacement with respect to said cutting element axially of said mandrel.

3. In a dental tool of the class wherein a cutting element is fixed in the end of a rotatable mandrel, the combination with said mandrel of a tongue guard generally planular in form and extending normal to the plane of the cutting element and of such length as to extend beyond the periphery of said cutting element, said guard being directly mounted on said mandrel for free rotational movement thereabout, and means on said mandrel cooperating with said guard to position said guard adjacent said cutting element and to maintain said guard against axial displacement and in protective relation with respect to said cutting element.

ROY E. HAWKINSON.
